Primary Examiner — Jeffrey D Asch(74) Attorney, Agent, or Firm — Morgan, Lewis & Bockius LLP(57) CLAIM

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof showing the open position.

The features in FIG. 8, which occur on an interior surface between the front and rear panels, are substantially flat, with no significant thickness or change of contour.

1 Claim, 6 Drawing Sheets(56)
